UNITED STATES PATENT OFFICE

2,413,576

HAIR EXTRACTING DEVICE

Harry Orner, Cleveland Heights, Ohio, assignor to
Maurice M. Cohen, Cleveland Heights, Ohio

Application November 2, 1944, Serial No. 561,565

6 Claims. (Cl. 128—355)

1

This invention relates to a hair extracting device and method for removing superfluous hair, and particularly to a device actuated automatically by a power source so as to grip a hair and extract the same.

Hair extracting devices heretofore have followed the general pattern of manually operated tweezers, by means of which the hair to be removed was gripped by claws and pulled to remove it. These devices are not entirely successful or satisfactory because (1) the mechanism for the proper motion results in cumbersome and complicated movement, (2) the appearance of the device promotes lack of confidence in its use, and (3) the safety of the device is limited to the skill of the operator since there is the ever-present danger of the reciprocating motion of the device causing the ends of the jaws of the device to penetrate the skin.

Another known form of hair extractor employs two tapered rollers arranged side by side with the peripheries engaging one another and the rollers are rotated in opposite directions so that hair is caught therebetween and extracted. These devices are cumbersome and cannot be manipulated to extract hair from a small defined area only. Furthermore, these devices cannot grip the hair close to the skin without danger of gripping or burning the skin. Also, considerable skill is necessary to operate these devices without causing considerable discomfort and possible injury by the inadvertent extraction of a plurality of hairs at one time. These devices are also subject to the second objection set forth in the preceding paragraph.

A feature of my device is the speed at which the actual extracting is done, so as to reduce to a minimum the unpleasant sensation incident to the extraction of a hair. Prior devices were limited in their speeds by the mechanism for reciprocating to the full length of the pull required to extract a hair or by the relative slow speed of the periphery of tapered rollers adjacent the tapered ends.

The principal object of the present invention is to provide a hair extracting device utilizing a rotary motion directly from the power source to two rotary surfaces rotatable about a common axis and movable relative to each other to grip a hair which is extracted by the continued rotary motion.

A further object of the invention is to provide a hair extracting device comprising a handle having a stem-like hair extracting unit extending from one end thereof, the unit having hair grasp-

2

ing faces arranged to present an annular slot-like opening for receiving hairs, the unit being rotated on its longitudinal axis and one face being moved toward and away from the other face during such rotation whereby hairs entering the slot formed between the faces are grasped and extracted by a rotary motion about the axis of the stem-like unit.

A still further object is to provide a safe hair extracting device which is devoid of sharp or pointed edges and which is attractive in appearance.

Still further the invention aims to provide a relatively small light-weight device suitable for feminine handling and incorporating few moving parts and thus resulting in economical construction.

A still further object of the invention is to provide a method of extracting hair, which method consists in grasping a hair and pulling the hair by a rotary motion.

Other objects and advantages of my invention will be apparent from the following description of preferred forms of my invention, reference being made to the accompanying drawing wherein:

Fig. 1 is a perspective view of the device showing the manner in which it is used;

Fig. 2 is a view on an enlarged scale showing the device mainly in longitudinal section;

Fig. 3 is a fragmentary view, partly in section and partly in elevation, on the same scale as Fig. 2, the section of the housing being taken substantially along the line 3—3 of Fig. 2;

Fig. 4 is a transverse sectional view taken substantially along the line 4—4 of Fig. 2, this view showing the cam face;

Fig. 5 is a fragmentary elevation with a portion broken away, showing a slight modification in the extracting end of the device; and

Fig. 6 is a fragmentary view, partly in section, showing an alternate form of thrust bearing.

Referring first to Fig. 2, there is provided a housing 1 having at its forward end a bearing 2 in which a sleeve 3 is free to rotate, the bearing 2 having a threaded connection with the housing 1. The sleeve 3 slides or reciprocates on a stem 4 which rotates with the sleeve 3 and for that purpose is fixed to a flexible shaft or other means 5 to which a prime mover is adapted to be attached to rotate it as well as the sleeve 3. Extending transversely entirely through the stem 4 is a pin 6 both ends of which extend into slots 7 at the rear end of the sleeve 3 in such a manner as to permit sleeve 3 to move axially on stem 4 while rotating with it (see Figs. 2 and 3).

On the face of the inside end or rear end of bearing 2 is a cam face 8 (see Figs. 2, 3 and 4) on which rides a follower 9. The follower 9 is fixed on the sleeve 3 by soldering or otherwise for causing the sleeve to move with the follower. A spring 10 abuts against the follower 9, urging it against the cam face 8 and is retained under compression by a collar 11 which is secured by a pin or otherwise to the stem 4. Secured to the housing 1 by screw threads or other suitable means is a retaining sleeve 12 against the forward end of which the collar 11 (with a suitable intervening washer) bears to keep the stem 4 from being urged backward by the spring 10. The follower 9, which, as stated before, is fixed to sleeve 3, causes the sleeve to reciprocate as the follower is moved over the cam face 8. Thus, the sleeve reciprocates relative to the stem 4.

The flexible shaft 5 is soldered or otherwise secured in a recess formed at the rear end of stem 4, as clearly shown in Fig. 2. The flexible shaft 5 is enclosed in a flexible housing or sheath 13 which extends practically the full length of the flexible shaft 5. A spring 14 is secured to the rear end of the retaining sleeve 12 and extends a short distance beyond the sleeve 12 so as to reinforce the housing or sheath 13 and protect it and the shaft against breakage.

The forward ends of the sleeve 3 and stem 4 project beyond the bearing 2, as clearly shown in Figs. 1 and 2. The sleeve 3 has at its forward end an annular clamping face 15 which is adapted, through the reciprocation of the sleeve, to be projected into contact with a similar annular face 16 of a head 17 formed at the forward end of stem 4 to clamp therebetween a hair to be extracted.

Cam face 8 (see Fig. 4) has a low land area 18 and a high land area 19 and an inclined area 20 extending from the low land area to the high land area 19. The cam face further has a fairly steep decline 21 from the high land area 19 to the low land area 18 (see Fig. 3), permitting the follower 9 (see Figs. 2 and 3) to move over the cam face 8 in a clockwise direction, the follower riding the inclined area 20 to the high land area 19 and causing the annular face 15 of the sleeve 3 to be moved away from the annular face 16 of the stem 4. A dwell on the high land area holds the face 15 spaced from the face 16 for a predetermined length of time. When approaching the relatively steep decline indicated by the line 21 on cam face 8, see Fig. 3, the follower is moved by the action of the spring 10, forcing the annular faces 15 and 16 together to grip a hair, and by the rotating motion imparted to the sleeve 3 and stem 4, the gripped hair is extracted from the skin. This constitutes a single cycle of the device which is repeated continuously and smoothly at relatively high speed.

It has been found that a spacing of about .015 inch between the faces 15 and 16 when the face 15 of the sleeve 3 has been retracted its full distance from the face 16 of the stem 4 is the most satisfactory to guide and grip a hair without pinching the skin. Thus, an arcuate slot-like opening is formed for receiving the hair to be extracted so that selected hairs in a limited area may be extracted without danger of inadvertently extracting other hair.

In Fig. 5 is illustrated a slightly modified form of the device, in which the annular faces for gripping the hair are somewhat differently constructed. In this form of the invention, a head 17' having an annular face 16' is formed on the

stem 4' substantially as in the first described construction. However, a head 25 is formed at the outer or cooperating end of the reciprocating sleeve 3', this head having a face 15' which cooperates with the face 16'. In this construction the area of the face 15' is greater than the area of the face 15 in the first described construction. It may be desirable to use this construction in order to facilitate locating or guiding short hairs into the space between the cooperating faces 15' and 16'.

With either form of my invention, the forward end or face 15 or 15' of the sleeve 3 or 3' is rapidly reciprocated with reference to the end of stem 4 or 4' into and out of contact with the face 16 or 16' of the stem 4 or 4'. At the same time both the sleeve and the stem are rapidly rotated. In the use of this device, the hair extractor end is placed against the face or other part of the body from which the hair is to be removed, and is moved back and forth by the operator until the hair to be extracted enters the space between the end of the sleeve 3 or 3' and the cooperating end of the stem 4 or 4'. Then the end of sleeve 3 or 3' moves into engagement with the end of stem 4 or 4', clamping the hair between the faces 15 and 16 or 15' and 16'. Then by the rotation of the stem and sleeve with the hair gripped between the faces for the interval allowed by the low land on the face of the cam, the hair is extracted.

Referring to Fig. 6, I have shown another form of construction wherein the thrust of spring 10 is taken by a roller bearing. A ball race member 30 is splined or otherwise secured to the stem 4 and a complementary ball race is formed in the sleeve 12 for retaining balls 31. This construction materially reduces friction and substantially eliminates vibration.

Also, another form of cam follower is shown. The cam follower 33 is secured to the sleeve 3 by soldering or by any suitable means. A pin 34 is press fitted into an opening 35 and a head 36 of suitable hardened metal is formed on the end of the pin. Preferably, the head is rounded and engages the cam face 8. The rounded head 36 presents a small surface to the cam and thereby minimizes friction. In this embodiment, the sleeve 3 is keyed to stem 4 by a pin 37 press fitted into an opening in the stem and extending into a slot 38 in the sleeve.

It will be seen that I have provided a hair extractor with the hair extracting end composed of two annular rapidly rotating parts with one of the parts moving into and out of engagement with the other so as to clamp the hair and extract the same by the rotation of both parts. This device has been found to operate very effectively without any possibility of injury to the skin and with the least amount of discomfort to the person being operated upon.

While I have shown the preferred construction and a slight modification, I do not desire to be confined to the precise details illustrated and described but aim in my claims to cover all modifications which do not involve a departure from the spirit and the scope of the invention.

Having thus described my invention, I claim:

1. A hair extractor comprising a relatively stationary portion having a stem projecting therefrom with a hair clamping face adjacent its extended end, a sleeve coaxial with said stem and having at its end a face adapted to cooperate with the first named face for clamping hairs between said faces, and means for rotating the stem and

sleeve and at the same time causing relative reciprocation of the stem and sleeve in an axial direction for alternately causing said faces to be brought into hair clamping and releasing relation so that a hair entering between the faces is clamped therebetween and extracted by continued rotation of the stem and sleeve and then released.

2. A hair extractor comprising a relatively stationary part, a stem projecting beyond said stationary part and having adjacent its extended end a hair gripping face, a sleeve coaxial with and slidable on the stem and having at its end a gripping face cooperating with said first mentioned face when the sleeve is moved on the stem in the direction of the first mentioned face for gripping hair between the faces, an annular cam located in the stationary part and adapted to reciprocate said sleeve on the stem, means for causing rotation of the sleeve and stem, and a spring actuated follower rotatable with the sleeve for causing relative reciprocating motion between the stem and sleeve.

3. A hair extractor comprising a stationary portion, a stem projecting beyond said stationary portion and provided adjacent its extended end with a hair gripping face, a sleeve coaxial with and slidable on the stem and having at its extended end a gripping face adapted to cooperate with the first named face when the sleeve is moved on the stem in the direction of the first mentioned face for gripping hair between the faces, a stationary annular cam in said stationary part, a cam follower secured to the sleeve, a spring arranged rearwardly of the follower and adapted to urge said sleeve forwardly, an abutment on the stem rearwardly of the follower and adapted to be engaged by said spring, and means for rotating the stem, the sleeve, the follower, the spring, and the abutment whereby the engagement of the follower with the annular cam will cause relative reciprocating motion between the stem and sleeve.

4. A hair extractor, or the like, comprising two members rotatable about a common axis, said members each having a circular hair gripping face, the centers of said faces coinciding with said

axis, one of said members being movable in opposite directions along said axis for moving said face thereof into and out of hair gripping relation with said other face; and means for rotating said members about said axis and for simultaneously moving said one member alternately in opposite directions for gripping and releasing hair between said faces.

5. A hair extractor or the like, including two members adapted to rotate about a common axis, each of said members having an annular hair gripping face, said faces having the axes thereof coincident with said axis and being disposed in confronting relation whereby hair interposed between said faces may be gripped and released by reciprocating movement of one of said members along said axis; means for simultaneously rotating said members about said axis in the same direction and at the same speed; and means for reciprocating one of said members in a direction longitudinally of said axis during rotation of said members for causing gripping and releasing of hairs between said faces during rotation of said members.

6. A hair extractor or the like, including two members adapted to rotate about a common axis, one of said members including a disk formation having the axis thereof common to the first mentioned axis, the peripheral area of one surface of said disk portion forming a hair gripping face, and the edge portions of the opposite surface of said disk portion being beveled toward the edge thereof, the other of said members having an annular face thereon having its center at said axis and being arranged in alignment with the hair gripping face of said disk, whereby hair may be gripped between said faces and then released when one of said faces is reciprocated along said axis; means for rotating said members about said axis in the same direction and at the same speed; and means for reciprocating one of said members in a direction longitudinally of said axis for causing said hair gripping faces to grip and release hairs during said rotation of said members.

HARRY ORNER.
